UNITED STATES PATENT OFFICE.

MICHAEL BRILLINGER, OF TORONTO, CANADA, ASSIGNOR OF ONE-HALF TO
ISAAC NEWTON DEVINS, OF SAME PLACE.

ELECTRIC SUBURBAN CAR.

SPECIFICATION forming part of Letters Patent No. 643,709, dated February 20, 1900.

Application filed August 31, 1899. Serial No. 729,087. (No model.)

To all whom it may concern:

Be it known that I, MICHAEL BRILLINGER, motorman, of the city of Toronto, in the county of York, in the Province of Ontario, Canada, 5 have invented certain new and useful Improvements in Electric Suburban Cars, of which the following is a specification.

My invention relates to improvements in electric suburban cars; and the object of the 10 invention is to devise a combined freight and passenger car in which the motorman will be in such a position as to have entire control of the trolley-pole-motor brake and be so located as to be entirely clear of the passengers 15 and freight and be enabled to see clearly before him along the line; and it consists, essentially, of a car having the passenger-compartment in the rear portion thereof and the freight-compartment in the forward portion 20 thereof, in the top of which latter compartment is located the motorman's compartment entirely separate therefrom, the trolley-pole being supported upon suitable standards on the inclined roof of the freight-compartment, 25 such trolley-pole being controlled from a cord extending into the motorman's compartment, and the parts being otherwise arranged and constructed in detail as hereinafter more particularly explained.

Figure 1 is a side elevation of my improved car. Fig. 2 is a longitudinal section. Fig. 3 is a front elevation.

In the drawings like letters of reference indicate corresponding parts in each figure.

A is the passenger-compartment of the car, and B the freight-compartment, which is provided with an inclined roof b at the forward end and the perpendicular front end b'.

C shows the wheels and truck.

D is the trolley-wire.

E shows the side doors and F the side steps leading into the passenger-compartment at the front, and G the side doors and H the side steps leading into the vestibule I at the rear 45 end of the car.

J is the motorman's compartment, which is provided with the usual controller j and also a suitable brake-operating mechanism. (Not shown and which is not necessary here to describe.)

j' shows the side windows of the motorman's

compartment, and j² the front or lookout windows.

B' shows the sliding doors of the freight-compartment, and B² shows the side windows 55 of the freight-compartment, and B³ the front windows.

K is an ordinary fender.

L shows the hand-rails, extending on each side to the door B⁴ of the motorman's compartment. l is the lower step for the motorman to mount the rungs l', leading to the door B⁴, which is preferably a sliding door.

M shows the side standards of the frame, upon the cross-bar m of which is pivotally supported the trolley-pole m', which is connected by a cord or rope m² to a ring or fastening m³ in the interior of the motorman's compartment J.

It will be seen that the motorman is removed away from the passengers of the car, 70 and consequently is not likely to be troubled by being asked questions or otherwise diverted from his duty. He is in excellent position for the control of the car, as he can see both forwardly over the slanting roof, under 75 the supporting cross-bar of the trolley-pole, and rearwardly over the car.

What I claim as my invention is—

1. In a motor-car, the combination with the passenger-compartment occupying the rear 80 portion of the car, of the freight-compartment occupying the forward portion and the motorman's compartment occupying the upper rear portion of the freight-compartment and extending up beyond the top of the car and provided with lookout-windows as shown and for the purpose specified.

2. In a motor-car the combination with the passenger-compartment occupying the rear portion of the car, of the freight-compartment 90 occupying the forward portion, the motorman's compartment occupying the upper rear portion of the freight-compartment and extending up beyond the top of the car and provided with lookout-windows, and the open 95 trolley-pole-supporting frame secured to the roof of the freight-compartment and leaving a clear space for outlook, and the trolley-pole pivoted on same and extending rearwardly and having the cord extending into the motorman's compartment as and for the purpose 100 specified.

3. In a motor-car the combination with the passenger-compartment occupying the rear portion of the car, of the freight-compartment occupying the forward portion, and having an inclined roof and the motorman's compartment occupying the upper rear portion of the freight-compartment and extending beyond the top of the car and provided with lookout windows as and for the purpose specified.
4. In a motor-car the combination with the passenger-compartment occupying the rear portion of the car, of the freight-compartment occupying the forward portion, the motor-

man's compartment occupying the upper rear portion of the freight-compartment and extending beyond the top of the car and provided with lookout-windows, the door in the side of the motorman's compartment, and the hand-rails and steps on the side of the car leading thereto as and for the purpose specified.

MICHAEL BRILLINGER.
